ILLUMINATED SIGN

Charles J. Wamser, Milwaukee, Wis.

Application October 2, 1936, Serial No. 103,650

1 Claim. (Cl. 40—130)

This invention pertains to illuminated signs, and more particularly to what are termed in the trade as skeleton window signs, which utilize an illuminated gas tube, such as neon, and so forth.

Heretofore, signs of the foregoing character have included frames for supporting gas tubes, but the electrodes, connections, and live parts, of the sign have been exposed, detracting from the appearance of the sign, and, more important, presenting a potential opportunity of serious injury to those coming in contact with the sign, such as window cleaners, and so on.

The present invention has primarily for its object to provide a skeleton sign utilizing a gas tube supported within a frame of tubular construction, which serves to house or encase the electrodes and live parts of the sign.

Incidental to the foregoing, a more specific object of the present invention resides in the provision of a sectional, tubular frame for supporting the gas tube and for housing the electrodes and other live connections.

A further object of my invention is to form a tubular frame of insulating material.

It is also an object to encase the sign in "Cellophane," or other transparent material, to protect the tubes against fly-specks and accumulation of dust, soot, and so forth.

With the above and other objects in view, which will appear as the description proceeds, the invention resides in the novel construction, combination, and arrangement of parts, substantially as hereinafter described, and more particularly defined by the appended claim, it being understood that such changes in the precise embodiment of the herein disclosed invention may be made as come within the scope of the claim.

In the accompanying drawings is illustrated one complete example of the physical embodiment of the present invention constructed according to the best mode so far devised for the practical application of the principles thereof.

In the drawings:

Figure 1 is an elevation of a sign constructed in accordance with one form of the present invention.

Figure 2 is an enlarged fragmentary section taken on the line 2—2 of Figure 1.

Figure 3 is a similar view taken on the line 3—3 of Figure 2.

Figure 4 is a fragmentary section taken on the line 4—4 of Figure 1.

Figure 5 is a detail section taken on the line 5—5 of Figure 1.

Figure 6 is a fragmentary section taken on the line 6—6 of Figure 5.

Figure 7 is a detail section taken on the line 7—7 of Figure 1, and

Figure 8 is a similar view taken on the line 8—8 of Figure 1.

Referring now more particularly to the accompanying drawings, the invention comprises a tubular frame designated generally by the letter F, and in that form illustrated is of a rectangular shape including upper and lower stretches 10, and side stretches 11, the ends of the stretches being connected by tubular corner brackets 12. Secured to the stretches 11, within the width of the frame, is a pair of horizontal supporting bars 13, to which are attached in any conventional manner the illuminating gas tubes 14, formed in conventional manner to provide characters or fanciful designs, and comprising the usual character strokes terminating in bent backs, or connecting portions 15, at the rear of the strokes.

As indicated in dotted lines in Figure 1, and also shown more in detail in Figures 5 and 6, the ends of the tubes 14 which carry the electrodes enter the frame and are housed by the same, as well as all connections between the electrodes and high tension cables.

Heretofore, in skeleton signs of the present type, it has been customary to merely fasten the illuminating tubes to a flat frame, with the electrodes and connections exposed, and, as stated in the objects of the invention, this structure is found highly objectionable, due to the potential danger to those coming in contact with the exposed connections, and, also, because of the unattractive appearance of the sign. Furthermore, the frames ordinarily employed were formed from relatively thin material, and due to the depth required in the bending of the tubes, the greater portions of the tubes were exposed above the face of the frame, subjecting the same to breakage in handling and shipping.

To overcome the foregoing objections, the present invention has been designed to provide an attractive frame, which both houses all live connections and forms an exceedingly rigid support for the tubes, and because of the thickness or depth of the tubular structure, it protects the tube to the extent that it is unnecessary for any portion of it to project beyond the front or rear faces of the frame, although in some instances this may be required, particularly where the characters or designs must extend beyond the area of the frame.

Considering now the details of construction

embodied in that form of the invention illustrated, both the stretches 10 and 11 are formed from front and rear channels 17 and 18, respectively, the same being connected by mortised 5 overlapping joints 19 and 20, respectively, and, as will be noted in Figures 4 to 6, inclusive, in the joint 20, which extends around the outer periphery of the frame, the same is mortised back to provide a groove or recess 21, for the 10 purpose to be hereinafter explained.

In securing the channel members together, either fiber insulating screws 22, cement, or any other suitable means, may be employed.

As best shown in Figure 4, the inner wall of 15 the channel 18 is provided with openings 23 for reception of the shouldered ends 24 of the horizontal supporting bars 13, to which the tubes 14 are attached, as heretofore explained, and with 20 particular reference to Figure 4, it will be noted that the supporting bars are positioned well to the rear of the frame, thus allowing ample space 25 for the strokes and bent backs of the tube.

As best shown in Figures 5 and 6, the ends of 30 the tubes, and their electrodes, are inserted through one of the channel members, and the necessary connections made prior to fastening the 35 channels together and connecting the same to the corner brackets 12. To permit insertion of the tubes the channel 17 is provided in one edge with a slot 19'. It will be noted, in referring to Figures 2, 3, 7, and 8, that corner brackets are 40 hollow and shouldered to receive the ends of the tubular stretches 10 and 11. As explained in connection with the attaching of the channels, 45 connection can be made between the stretches and angle brackets by cement, insulating screws, or other fastening means.

From the foregoing, it will be noted that a 40 tubular frame of exceedingly neat appearance has been fabricated, and while the same has been illustrated as being rectangular, and having angle corner brackets, it will be obvious that the same may be of any desired shape, such as round, 45 triangular, or hexagonal, without departing from the structure and principle thus far described.

Considering now the mechanism illustrated for attachment of the high tension cables 28, and with particular reference to Figure 2, it will be noted that the bracket 12 is provided with a 50 recess 25 for reception of a knurled metallic nut 26, that in turn receives a threaded pointed plug 27, the end of which enters a restricted opening in the nut 26. The end of the cable is then stripped of its cover to expose the wire 28 that 55 is projected through the restricted opening in the knurled nut 26, and spread by the pointed plug 27 to provide a secure and perfect connection with the cable. The plug 27 may be provided with any type of connector, such as the "Pahnstock" clip 29, to which a line from one of the 60 electrodes is attached.

Tightly fitted over the nut 26 is an insulating sleeve 30, which may also be secured to the cable by an insulating set screw 31. Obviously, the purpose of the insulating sleeve 30 is to prevent contact with the metallic nut 26.

The sign may be supported by the high tension cables 28, or, if desired, rods or wires 31 may be attached to the brackets 12, or to any other portion of the frame.

As previously explained, in some instances it 10 is proposed to encase the entire sign in Cellophane, or other inexpensive transparent sheets of material, and this may be accomplished in one simple manner by placing sheets 35 over the front and rear faces of the frame, overlapping their ends in the recess 21, and securing the same by an ornamental strip 32 of any desired material.

In carrying out the foregoing purpose, it will 15 also be noted that the outer faces of the brackets 12 are also provided with recesses 21', which align with those formed in the stretches 10 and 11, and permit the use of a continuous locking band 32, with the exception of slight interruption 20 at the points where the high tension cables enter 25 the frame.

In the preferred form of the invention, it is proposed to construct the channels and corner brackets of insulating material, preferably a composition which can be cast or moulded. However, 30 it is also contemplated that a metallic tubular frame may be employed by providing the interior of the same with suitable insulation to avoid contact with the frame and connections housed within the same. Also, while the frame is shown 35 rectangular in cross section, it will be understood that the same may be round, square, or of other tubular form. Lastly, while it is essential that the stretches be formed in sections, it is not necessary that the mortised lapping joints be used 40 for assembling, although it is believed that this structure develops the best results, from the standpoint of manufacture, utility, and appearance.

From the foregoing it will be apparent that a 45 highly novel type of sign has been provided, which adds little to the cost of conventional skeleton display signs, and at the same time overcomes all of the objectionable features encountered in the same.

I claim:

An illuminated skeleton display sign comprising, a tubular frame consisting of stretches split longitudinally to provide access to the interior of the frame, means for securing the sections 55 together, brackets connecting the ends of said stretches, a support carried by said frame, and a gas tube attached to said support and having its electrodes and connections housed within said frame.

CHARLES J. WAMSER.
